HUGO GRIESHABER, OF NEW LONDON, CONNECTICUT, ASSIGNOR TO ELECTRIC BOAT COMPANY, OF NEW YORK, N. Y., A CORPORATION OF NEW JERSEY.

LIFE-BUOY FOR SUBMARINE OR SUBMERGIBLE BOATS.

1,137,131.

Specification of Letters Patent.

Patented Apr. 27, 1915.

Application filed October 15, 1913. Serial No. 795,189.

To all whom it may concern:

Be it known that I, HUGO GRIESHABER, a citizen of the United States, residing at and whose post-office address is New London, 5 county of New London, and State of Connecticut, have invented certain new and useful Improvements in Life-Buoys for Submarine or Submergible Boats; and I do hereby declare the following to be a full, 10 clear, and exact description of the invention, such as will enable others skilled in the art to which it appertains to make and use the same.

The present invention relates to man-carrying life-buoys for submarine or submergible boats, and particularly to one normally held in an exterior launching pocket in the boat by the pressure of the sea in such manner as to permit the discharge of the buoy 15 from the launching pocket at will by mechanism within the boat, or within the buoy, or in both places, said buoy having a substantially water-tight compartment with means for the passage of a man thereinto 20 from the interior of the boat when the buoy is in its place in the launching pocket, and also having means for egress therefrom when the buoy is floating at the surface of the sea. In the preferred construction, the 25 buoy is provided with a float to keep it buoyant even when the compartment is filled with water, and is associated with a drum operable from the interior of the boat and connected to the buoy by a flexible connection 30 so that the buoy may be drawn back from the surface of the sea within the launching pocket after each member of the crew reaches the surface. In this way, 35 facility is afforded for the escape of all members of the crew, including the last man, and by mechanism which may if desired be operated by hand independent of the power driven mechanism in the boat.

The preferred form of construction for carrying out the idea embodied in my invention in application to a submergible torpedo boat, as an example, is illustrated in the accompanying drawings, in which—

Figure 1 represents a section through the launching pocket of the boat and through the buoy seated therein; and Fig. 2 represents an elevation of the buoy at right angles to Fig. 1.

The launching pocket 1 of substantially circular outline and having the outwardly

diverging end portion 2, is formed on the exterior of the boat 3 at any suitable place, but preferably at the top thereof so that the buoy may rise vertically from the pocket without obstruction. The circular member 4 has a ground beveled seat 5 adapted to coact with the ground beveled seat 6 on the buoy, so that the joint formed between them is substantially water-tight. The launching pocket extends below the buoy and forms a substantially water tight space 7 from which the water may be removed at will through the pipe 8 by means of a hand-operated or a power-driven pump within the boat.

The life-buoy is made of suitable material 70 as metal and comprises a compartment 9 suitable for holding a man, and an air tank 10 forming a float capable of keeping the buoy buoyant even when the compartment 9 is filled with water. The doors 11 and 12 75 open outward from the top and bottom respectively of the compartment 9 and are self-closing with a substantially water-tight fit. The conduit 13 having the valve 14 within the compartment 9 leads from a place 80 above the seat 5, 6 to a place below it, so that a man within the compartment may admit water from the sea to the space 7. In this way, the pressure of the sea on the buoy may be equalized and the buoy allowed 85 to rise to the surface. The drum 15 is connected to the buoy by a suitable flexible connection 16, and it is operable from within the boat by means of the hand crank 17.

Normally the space 7 is maintained free 90 of water by pumping the water out through the pipe 8. The buoy is thereby subjected to the pressure of the sea to hold it in place in the launching pocket and to maintain a substantially water-tight joint at 5, 6. If 95 it now becomes necessary for the crew to leave the submerged boat, the door 18 is opened to allow a man to pass through the compartment 7 and into the buoy through the door 12. After the doors 12 and 18 100 are closed, the space 7 is filled with water either through the pipe 8 or the conduit 13. The pressure of the sea on the buoy becomes equalized as soon as the space 7 is filled with water, and the buoy then quickly 105 rises to the surface of the water and floats there in an upright position as a result of the buoyancy of the air tank 10. The man within the compartment then opens the door 11 and climbs out of the buoy, whereupon 110

the door closes. The buoy is pulled back into its place in the pocket and the operation is repeated for each of the remaining members of the crew, the water first being 5 pumped out of the space 7 after each operation. In this way all the members of the crew of the submerged boat may escape in turn, and the last one would close the door 10 before entering the buoy in order to prevent flooding of the boat after the buoy leaves the pocket. The position of the floating buoy indicates the location of the boat for purposes of salvage.

Having thus described my invention, 15 what I claim is:—

1. A submarine or submersible boat having a launching pocket constituting a guide-way and receptacle for a life-buoy, a conical valve seat in said pocket, a man-carrying 20 life-buoy having a member coacting with said seat to form therewith a closure, and to form a substantially water-tight space in the lower portion of the pocket, means operable from within the boat for removing water from said space to subject the buoy to the pressure of the sea and thereby force it onto the valve seat, means for admitting water to said space to equalize the pressure and permit the buoy to rise to the surface, and means for retracting the buoy from the surface into the pocket, substantially as described.
2. A submarine or submersible boat having a launching pocket constituting a guide-way and receptacle for a life-buoy, a conical valve seat in said pocket, a man-carrying 25 life-buoy having a member coacting with

said seat to form therewith a closure, and to form a substantially water-tight space in the lower portion of the pocket, means 40 operable from within the boat for removing water from said space to subject the buoy to the pressure of the sea and thereby force it onto the valve seat, means operable from within the buoy for admitting water to said 45 space to equalize the pressure and permit the buoy to rise to the surface, and means for retracting the buoy from the surface into the pocket, substantially as described.

3. The combination with a submarine or 50 submersible boat having an exterior launching pocket, of a man-carrying life-buoy having a substantially water-tight compartment and adapted to seat in the pocket in such manner as to form a substantially 55 water-tight space therein, means affording passage from the interior of the boat, to the compartment, means for removing water from said space to subject the buoy to the pressure of the sea to hold it seated in position, a valved-conduit within the compartment adapted to admit water from the sea to said space to equalize said pressure and thereby allow the buoy to rise to the surface of the sea, and supplemental means operable 60 from within the boat for admitting water to said space, substantially as described.

In testimony whereof I affix my signature, in presence of two witnesses.

HUGO GRIESHABER.
